FIG. 17

Fig. 16

UNITED STATES PATENT OFFICE.

HAROLD H. PELZER, OF NEW YORK, N. Y.

MACHINE FOR APPLYING AND GUMMING LABELS, WRAPPERS, AND THE LIKE.

Application filed August 2, 1924. Serial No. 729,724.

My invention herein described has for its object to provide devices to automatically apply and gum labels or wrappers to articles such as chewing gum, paired shoe laces, 5 cigars, candy, and the like, in a positive, efficient and simple manner.

Another object is to provide a machine which is inexpensive to build, occupies little space, requires little attention, and is not 10 liable to get out of order.

Other objects will be evident from the following specification and appended claims.

In order that the invention may be better understood, attention is directed to the accompanying drawings, forming part of this 15 specification, in which:

Fig. 1 is a central sectional elevation with parts broken away;

Fig. 2 is a sectional view on the line 2—2 20 of Fig. 1, looking in the direction of the arrow 2;

Fig. 3 is a detail elevation of the folding fingers, in upward position for the first 25 folding operation, and with their actuating means;

Fig. 4 is a sectional view of Fig. 3 on the line 4—4, and looking in the direction of the arrow 4;

Fig. 5 is a detail elevation of the moistening pad with its actuating mechanism;

Fig. 6 is a detail elevation of the folding slide for the second folding operation, with its operating parts;

Fig. 7 is a detail plan view of the folding 35 slide for the second folding operation;

Fig. 8 is a detail view illustrating the relative positions of the folding fingers and moistening pad at the start of the first step in folding the label;

Fig. 9 is a detail view of the same illustrating relative positions at the end of the first folding operation;

Fig. 10 is a detail view of the same illustrating relative positions during the first 45 stage of the moistening operation;

Fig. 11 is a detail view of the same during the second stage of the moistening operation, showing the action of the folding slide at the beginning of the second folding operation;

Fig. 12 is a detail view of the same at the

completion of the moistening operation, and of the second folding operation;

Fig. 13 is a detail view of the same at the completion of the second folding operation, the folding fingers being in their lower position;

Fig. 14 is a detail of the same, illustrating relative positions at the beginning of the conveyer chain movement;

Fig. 15 is a detail view, as in Fig. 14, illustrating the relative position of the parts at the end of the conveyer chain movement;

Fig. 16 is a detail elevation of a modification of Figs. 8 to 15, illustrating a single folding finger for the first folding operation 65 in its upward position to be used with a twin chain conveyer;

Fig. 17 is a detail elevation of the same showing the folding finger in its lower or retracted position; and

Fig. 18 is a sectional view of Fig. 17 on the line 18—18 and looking in the direction of the arrow 18.

In the above views the corresponding parts are represented by the same reference numerals.

Attention is first directed more particularly to Figs. 1 and 2 in which a chain conveyer 1 has fastened thereon the carriers 2 by means of the countersunk screws 3 on the specially formed links 4. The carriers 2 are suitably designed to receive the articles to which the labels are to be applied. The particular machine of the drawings shows U-shaped carriers which are suitable for handling shoe laces. The chain conveyer 1 is shown meshing with a sprocket wheel 5, it being understood that a corresponding sprocket wheel meshes with the conveyer chain at the left of the drawings. The sprocket wheel 5 is locked on the shaft 6 by means of the lock pin 7 driven through the sprocket wheel hub and shaft, as will be understood. The shaft 6 runs in suitable anti-friction bearings in the side frames 8 and 9 and is driven in a manner to be hereinafter explained. The upper portion of the chain conveyer 1 rides upon a rail 10 which is centrally supported between the side frames 8 and 9 by means of the supports 11 100

which are held in position and horizontally adjustable by means of the adjusting screws 12 (Fig. 2) in the side frames 8 and 9.

Driven into the side frames 8 and 9 are the bushings 12^a (Fig. 2) in which the cam shaft 13 is free to run, being rotated in a clockwise direction as indicated by the arrows. Mounted upon the cam shaft 13 are the cams 14, 15 and 16 for the sliding folding plate, the folding finger, and the moistening pad, respectively.

Cooperating with the cam 14 is the roller 17 (Figs. 1 and 6) on the shoulder pin 18 fastened on the lever 19 which is rigidly secured to the shaft 20 protruding through, and free to rotate in suitable bearings in the side frames 8 and 9. Upon the outer ends of the shaft 20 (Fig. 2) are secured the levers 19^a the upper ends of which are slidably attached to the arms 21 of the sliding folding plate 22 by means of the shoulder pin 23 securely fastened to the arms 21, and which rides in an elongated slot in each lever 19^a, as shown in dotted lines in Figs. 1 and 6.

The sliding plate 22 slides upon the top of the side frames 8 and 9 and in a cut-out portion of the plate 24 which is fastened to the side frames 8 and 9 by means of screws 25 (Fig. 7). The arms 21 of the sliding plate 22 extend through the slots 26 cut in the plate 24 (Figs. 5 and 7), to allow the free movement of the plate forward and backward. Screwed into the sliding plate 22 and passing through the slot 27 (Figs. 6 and 7) in the plate 24 is the screw 28, about which is hooked one end of the coil spring 29, the other end of which is hooked about the anchor screw 30 screwed into the plate 24. The front end of the sliding plate 22 (Fig. 7) is provided with the protruding portion or finger 22^a, and with the shoulder 22^b, the purpose of which will be described hereafter.

Riding in contact with the face of the cam 15 (Figs. 1, 3 and 4) is the roller 31 on the shoulder pin 32 fastened in the gear sector 33 which rotates on the shoulder portion of the pin 34 (Figs. 3 and 4) mounted in side frame 8. Meshing with the teeth of the gear sector 33 is the pinion 35 rigidly secured on the shaft 36 which is free to rotate in suitable bearings in the side frames 8 and 9, as shown in Figs. 2 and 4. Around the shaft 36 is the coil spring 37, one end of which is fastened into the pinion 35, with its other end anchored in the rail 10. Arms 38 are also rigidly secured to the shaft 36 (Figs. 1, 8 to 15), and these arms have pivotally attached thereto by means of the pivot screws 39 the folding fingers 40 having an extended leg portion 40^a, the purpose of which will be described hereafter. The small coil springs 41 (see particularly Fig. 4) are held in position by the pivot screws 39, and each has one end anchored by the

corresponding arm 38 and the other end bears against the corresponding folding finger 40. Screwed into the side frames 8 and 9 (Figs. 2 and 4) are the trip pins 42 which cooperate with the folding fingers as will be described hereafter.

Engaging the face of the cam 16 (Figs. 2 and 5) is the roller 42 rotatably mounted on the pin 43 secured in one end of the lever 44 which is free to rotate on the bushing 45 located on the outer end of the pin 34. Secured in the upper end of the lever 44 is the pin 46, upon the shoulder portion of which is the roller 47 (Figs. 2 and 5) free to roll in the slot 47^a in the end of the lever 48 fastened on the shaft 49 (Fig. 2). The lever 48 is provided with a collar 48^a which is secured to the shaft 49, the latter being free to rotate within the long bearing 24^a carried by the plate 24. On the other end of shaft 49 is fastened the lever 50 which has integral therewith the moistening pad block 51, which carries the moistening pad 52 (Figs. 2 and 5). Screwed into the block 51 (Figs. 1 and 5) is the nipple 53 over which is slipped one end of the flexible tubing 54, the other end of which is slipped over the outlet of the pet-cock 55 screwed into the face of the reservoir 56 carried by a standard 57, the latter being held in position by means of the screws 58 through plate 24. A coil spring 59 has one end hooked in a hole in the lever 50 and the other end is anchored in a hole in the standard 57.

Fastened to the tops of the side frames 8 and 9 (Figs. 1, 2, 4, 7) are the plates 61, there being sufficient clearance between the ends of these plates 61 to allow for free passage of the carriers 2. Also secured to the side frames 8 and 9 is the plate 62 which extends across the entire width of the machine and is curved on a radius (not shown) to conform with that of the conveyer chain and to just clear the U-shaped carriers when they are moved around by the sprocket wheel 5. At the lower end of and so fashioned as to extend above the plate 62 (Fig. 1) are the ejector fingers 63 which are securely held in position on the stationary shaft 64 by means of the blocks 65 and screws 66. The purpose of these plates and operation of the ejector fingers will be later described.

Having now identified the various parts of my improved machine, I will now proceed with a description of its operation.

The labels or wrappers L and the articles A about which the labels or wrappers are to be fastened, are deposited into the U-shaped carriers (Figs. 8 to 15) either by means of suitable mechanism for that purpose or by the hand of an operator. This operation is carried on in proper timing with the mechanism for driving the machine. The driving mechanism employed may be the well known Geneva movement to give

to the sprocket wheel shaft 6 an intermittent or step-by-step movement. The cam shaft 13 is rotated continuously and the cams 14, 15 and 16 are so positioned that proper timing relation may be had between the various operating parts and the stop and start motion of the conveyer chain 1. Each forward movement of the conveyer chain 1 brings the following U-shaped carrier up to the leading edge of the plate 24 (Fig. 1) where it is given a period of rest long enough to allow for moistening the gummed portion of the label and folding its ends down. This folding operation I will now describe, referring particularly to Figs. 8 to 15 inclusive, which illustrate the relative positions of the parts during one complete revolution of the cam shaft 13.

Figs. 8 and 9 show the carrier 2 just after it has come to rest, the arm 38 having been swung upward. This upward swing of the arm 38 begins shortly before the carrier comes to rest and receives its motion by means of the roller 31 taking the rise of the cam 15 (Figs. 1 and 3). The cam 15 is revolved in a clockwise direction and on raising the roller 31 upward revolves the gear sector 33 in a counter clockwise direction causing the pinion 35 to revolve in a clockwise direction, thus swinging the arms 38 upward. During the upward swing of arms 38 the extended legs 40^a of the folding fingers 40 come in contact with the trip pins 42 as shown in Fig. 8. This causes the folding fingers 40 to swing inward toward the center of the machine (Fig. 4). This inward swing of the folding fingers 40 is so timed as to allow them to clear the chain conveyer 1 and when the swinging movement has been completed the ends of the fingers 40 have passed above the carrier 2 causing one end of the label L to be folded down upon the article A (Figs. 3, 8 and 9). At this point the roller 31 is riding on the dwell of the cam 15 (Fig. 3) causing the fingers 40 to remain in this position for reasons more fully described hereinafter.

At this point the roller 42 which has been running on the dwell of the cam 16 causing the moistening pad to be held upwards, comes in contact with the fall of the cam 16 (Fig. 5) thus allowing the coil spring 59 which is under tension to pull the arm 50 sharply downward and inward, bringing the moistening pad 52 in contact with the gummed portion of the label L as shown in Fig. 10. The moistening pad block then immediately starts to swing backward and upward again (Fig. 11) due to the roller 42 taking the rise of the cam 16, causing the lever 44 to be oscillated in a counter clockwise direction and forcing the arm 48 to be swung backward and upward in a clockwise direction, thus partially rotating the shaft 49 and swinging the arm 50.

During the first part of this backward swing of the moistening pad 52 the sliding folding plate 22 is moved forward at the same rate of speed that the pad is receding, thereby causing a wiping action of the gummed surface of label L on the moistening pad, as shown in Fig. 11. The sliding folding plate 22 receives its motion from the roller 17 riding the rise of the cam 14, thereby oscillating the levers 19 and 19^a on the shaft 20 for that purpose (Fig. 6). This wiping action of the label against the moistening pad is caused by the protruding portion or finger 22^a of the sliding plate 22 which passes between the folding fingers 40 (Fig. 4) and thus holds the folded end down before the folding fingers 40 are swung out and downward to their normal position (Figs. 12 and 13). The folding fingers are swung outward by means of the springs 41 actuating upon the fingers, as the extended leg portions 40^b thereof contact with the trip pins 42 during the movement of the arms 38 from the position of Fig. 12 to Fig. 13. This movement of the arms 38 is effected by the coil spring 37 turning the shaft 36. The folding fingers start to recede from the label before the sliding plate 22 has finished its forward movement, allowing a clearance for the shoulder 22^b of the sliding plate 22 which insures the folding down smoothly across its entire width of this end of the label which had not been folded up to this point (Fig. 13). At this point the conveyer chain 1 starts to move, and at the same time the sliding folding plate 22 recedes with it (Fig. 14) until it reaches the end of its movement, but the conveyer chain continues on until the next carrier 2 is in the position as shown in Fig. 15, where it is brought to rest by means of the Geneva movement, and the folding and moistening operations are ready to start over again. The sliding folding plate 22 is brought back to its normal position by means of the coil spring 29, the roller 17 riding down the fall of the cam 14.

With each successive folding and moistening operation the carriers 2 bring the labelled articles or packages back under the sliding plate 22, and from there they ride under the plate 62. These plates hold the gummed ends of the labels down firmly, allowing enough time for the two ends of the label to firmly adhere. As the packages or articles reach the lower end of the plate 62 (Fig. 1) they are pushed out of the carriers (which are now up-side down) by the stationary ejector fingers 63, which will be clearly understood from Fig. 1.

The object of the plates 61—61 (Fig. 4) fastened on the side frames 8 and 9 is to insure the holding down into the carriers 2 of the articles or packages to be labelled before the label is folded down around them.

As a modification of my invention, Figs. 16, 17 and 18 show the use of a single folding finger or arm 38^a in place of the folding fingers 38 described above. The method of raising and lowering this folding arm 38^a is identical with the method already described for actuating the arms 38, the main difference being in the use of a twin chain conveyer 1^a for two sets of carriers riding on two rails, thereby allowing the use of a single folding arm rising upward between them. The folding arm 38^a is cut or slotted away at its lower end to allow the pinion 35 to be placed in position (Fig. 18) and the shoulered portion of the pin 34 is lengthened and likewise the hub of the gear sector 33. The method of bringing the folding arm 38^a back to its normal position is the same as that already described, excepting that one end of the coil spring 37 is fastened in the folding arm 38^a instead of the hub of the gear 35. The other end is anchored in the side frame 9 instead of the rail 10. The timing and operation of this modified folding arm are the same as already described. With this type of twin chain conveyer a very much wider label and article or package can be handled than when a single chain conveyer is used.

I do not desire to limit myself to the precise details of construction and arrangement above described as it is obvious that various modifications may be made therein without departing from the essential features of my invention as defined in the appended claims.

I claim:

1. In label applying or wrapping mechanism, the combination with a conveyer for conveying the articles to be wrapped successively to the labelling or wrapping devices, of a finger for folding a free end of the label or wrapper upon the article, a pad for gumming or moistening the underside of the other end of the label, a slide for folding down such other end, and mechanism for causing the folding finger to retreat as the slide advances, substantially as set forth.

2. In label applying or wrapping mechanism, the combination with a conveyer for conveying the articles to be wrapped successively to the labelling or wrapping devices, of a plurality of fingers for folding a free end of the label or wrapper upon the article, a pad for gumming or moistening the underside of the other end of the label, a slide for folding down such other end, and mechanism for causing the folding fingers to retreat as the slide advances, substantially as set forth.

3. In label applying or wrapping mechanism, the combination with a conveyer for conveying the articles to be wrapped successively to the labelling or wrapping devices and means for operating said conveyor with a step-by-step movement, of a plurality

of pivoted fingers for folding a free end of the label or wrapper upon the article during the periods of rest, a pad for gumming or moistening the underside of the other end, a sliding plate, and mechanism for causing the folding fingers to retreat as the sliding plate advances, substantially as set forth.

4. In label applying or wrapping mechanism, the combination with a conveyer for conveying the articles to be wrapped successively to the labelling or wrapping devices and means for operating said conveyer with a step-by-step movement, of a plurality of swinging and pivoted fingers for folding a free end of the label or wrapper upon the article during the periods of rest, a pad for gumming or moistening the underside of the other end, a sliding plate, and mechanism for causing the folding fingers to retreat as the sliding plate advances, substantially as set forth.

5. In label applying or wrapping mechanism, the combination with a conveyer for conveying the articles to be wrapped successively to the labelling or wrapping devices, of a plurality of fingers for folding a free end of the label or wrapper upon the article, a pad for gumming or moistening the underside of the other end of the label, a slide for folding down such other end, said slide being formed with a projection entering the space between said folding fingers, and mechanism for causing the folding fingers to retreat as the slide advances, substantially as set forth.

6. In a label applying or wrapping mechanism, the combination with a conveyer for conveying the articles to be wrapped successively to the labelling or wrapping devices, of a finger for folding over one end of the label or wrapper, a pad for gumming or moistening the underside of the other end of the label or wrapper, a slide for folding over such other end, and a continuous plate with which the wrapped or labelled article makes contact after wrapping or labelling to provide time in which the gum may dry, substantially as set forth.

7. In a label applying or wrapping mechanism, the combination with a conveyer for conveying the articles to be wrapped successively to the labelling or wrapping devices, of a finger for folding over one end of the label or wrapper, a pad for gumming or moistening the underside of the other end of the label or wrapper, a slide for folding over such other end, a continuous plate with which the wrapped or labelled article makes contact after wrapping or labelling to provide time in which the gum may dry, and means for ejecting the articles after wrapping or labelling successively from the conveyer, substantially as set forth.

8. In a label applying or wrapping mechanism, the combination with a conveyer for

conveying the articles to be wrapped successively to the labelling or wrapping devices, of a pair of swinging arms movable toward and away from the article to which the label or wrapper is to be applied, a pair of pivoted wrapping fingers carried by said arms and engaging one end of the label or wrapper to fold the same on the article,

means for gumming or moistening the other end of the label, and means for folding such other end of the wrapper or label on to the first folded end, substantially as set forth.

This specification signed and witnessed this 1st day of August, 1924.

HAROLD H. PELZER.
